UNITED STATES PATENT OFFICE

2,506,053

WEB CUTTING AND ASSOCIATING MEANS
FOR PRINTING MACHINESAdolph M. Zuckerman, New York, N. Y., assignor
to R. Hoe & Co., Inc., New York, N. Y., a cor-
poration of New York

Application February 15, 1945, Serial No. 573,045

1 Claim. (Cl. 270—18)

1
The present invention relates to web printing machines, and more particularly to machines in which one or more webs are printed, then slit into a plurality of ribbons that are turned and associated in face to face relation, and then forwarded to a cutting and folding mechanism, which delivers the products in the form of signatures.

An object of the invention is to provide means whereby each of the ribbons will be so guided to the associating mechanism, that the printing thereon will be in accurate register, transversely of the running ribbon, with the printing on other ribbons associated therewith.

Other objects of the invention will be apparent from the following description and claim.

A preferred embodiment of the invention is illustrated in the accompanying drawings, wherein:

Figure 1 is a diagrammatic elevational side view of a printing machine showing turning bar and folding mechanisms, associated therewith;

Figure 2 is a diagrammatic end view of the mechanism shown in Figure 1 as viewed in the direction of the arrow 2, of Figure 1, some of the parts shown in Figure 1 being omitted;

Figure 3 is an enlarged diagrammatic view partly in perspective of a portion of the mechanism shown in Figures 1 and 2, and showing a schematic wiring diagram;

Figure 4 is a plan view of a portion of the mechanism shown in Figure 2; and

Figure 5 is a section as viewed along the broken line 5—5 of Figure 4, as seen in the direction of arrow 5.

A printing machine is herein shown having a plurality of printing couples each provided with an impression cylinder 11, (Figure 1) a printing or plate cylinder 12, and an inking mechanism 13, which coact to perfect a web W as it passes through the printing couples. Thereafter the web is carried over guide rollers 14 to a web slitting mechanism having a plurality of slitting knives 16, cooperating with a slitting roller 17. The slitting roller 17 is journaled in frame members 18 and 19, (Figure 4) and carries a bevel gear 21, that meshes with a bevel gear 22 secured to a shaft 23 driven in a known manner from the printing machine drive. The slitting knives 16, are secured to a shaft 24 rotatably mounted in bearings 26 formed at one end of brackets 27. The other end of the brackets 27 are mounted on a cross bar 28, the opposed ends of which are supported by the frame members 18 and 19. A gear 31, secured to the shaft 24,

2
is in mesh with a gear 32 secured to the shaft of the roller 17, and the slitting knives 16 are thus rotated to slit the web W into a plurality of ribbons R1, R2, R3 and R4. It will be understood that presser rollers (not shown) may be used to press the ribbons into firm contact with the roller 17.

A turning bar 33 is positioned to change the direction of movement of each ribbon R1, R2, R3 and R4 to a direction approximately 90 degrees from its direction in moving from the slitter, and to position the ribbons so they are brought into face to face relationship. Preferably all of the turning bars 36 and associated mechanisms are identical, and one end of each turning bar 36 is rigidly secured to a bracket 37 by a bolt 38, while the other end of each turning bar is rigidly secured to a bracket 51 by a bolt 52. A channel portion 39 (Figure 5) of each bracket 37 rests on the top of a cross member 41, and the bracket is held to limited motion on the member 41 by a bolt 42 passing through a slotted hole 43. In like manner each bracket 51 rests on the top of a cross member 53, and is held to limited motion on the member 53 by a bolt 54 passing through a slotted hole 55. A lug 44 (Figure 3), formed as a part of the bracket 37, has a threaded hole 46 through which a threaded shaft 47 is screwed. A coupling 48 connects the shaft 47 with the output shaft of a combined gear reducer and motor 49 supported from the member 41. By rotating the motor shaft in a forward or reverse direction, the bracket 37 may be moved along the member 41 within the limits of the slotted hole 43. Moving the bracket 37 lengthwise of the member 41 (Figure 4), causes the bar 36 and the bracket 51 to move correspondingly.

Each ribbon, after being turned about its turning bar is led about a fixed roller 56 (Figure 2) and a compensating roller 57, that is movably supported on a swingable bracket 58. Each compensating roller, in a known manner, may be adjusted to vary the length of the ribbon running over it. After leaving the compensating roller 57, each ribbon as it passes over a roller 61 is scanned in a manner hereinafter described, by a light sensitive scanning head 59 (Figure 3). Thereafter the plurality of ribbons are assembled face to face and led together between cooperating forwarding rollers 62 and 63 (Figures 1 and 2), from which the assembled webs pass over a former 64, between leading-in rollers 66, nipping rollers 67, pulling rollers 68, over a second former 69, between leading-in rollers 71, nipping rollers

72, and thence to a folder, indicated generally by the numeral 73.

Preferably one of the pairs of printing couples will print a line of register marks 74 in the center of each ribbon formed from the web W by the slitting knives 16.

In a known manner, each scanning head 59 will view the series of register marks 74. The scanning head 59 (Figure 3) and associated mechanisms provided for each turning bar may be constructed and connected in accordance with the arrangement shown in U. S. Cockrell Patent 2,356,567, granted August 22, 1944, although any other suitable device and arrangement may be used. As herein shown, the scanning head 59 includes a source of light 76, a light sensitive device, such as a photoelectric cell 77, a disc 78, carrying a plurality of lenses 79, a synchronous motor 81 for rotating the disc, and motor controlling devices contained within an enclosure 80, which devices may correspond with devices shown and described in the patent hereinbefore mentioned. The scanning head 59 detects any lateral deviation of the register marks 74 from a predetermined correct position, and in response to variations in the current passing through the light sensitive device 77, the motor 49 is rotated forward or backward to move the turning bar 36 back and forth on the members 41 and 53, and thus to automatically adjust the ribbon to maintain the register marks in a predetermined position transversely of the direction of movement of the ribbon. When the several scanning heads 59 (Figures 2 and 4) are adjusted to position the register marks 74, on each of the ribbons directly over one another as the ribbons pass between the forwarding rollers 62 and 63, the printing will be in accurate lateral register, and the signatures as delivered will have properly proportioned margins at each side of each page.

When threading ribbons through the printing machine, it is sometimes desirable to manually adjust some of the turning bars 36. To provide means for such operation, a switch 82 is supplied for each motor 49, by means of which it can be disconnected from the automatic control, and connected to an external source of power 84. The switch 82 when in the normal position shown by solid lines in Figure 3, connects the brushes of the motor 49 to a pair of wires 83 connected to controlling devices in the enclosure 80 that receive current from a circuit 85. With the switch in this position, the motor will adjust the position of the turning bars 36 in response to indications received by the scanning head 59. If the switch 82 is moved to the left, the motor 49 will be disconnected from the wires 83 and connected to the source of power 84, and the motor 49 will then operate in one direction. If the switch 82 is moved to the right, the motor will be disconnected from the wires 83 and connected to the source of power 84 in the reverse

direction, causing the motor to operate in a direction opposite to that previously described.

In operating the mechanism disclosed herein, if any ribbon becomes displaced transversely, its scanning head will energize the proper motor 49, which in turn will move the proper turning bar to correct the position of the displaced ribbon.

The mounting of the turner bars on the slides 37 and 51 at the opposite ends thereof and the guiding of these slides on tracks 41 and 53 insures that each of these turner bars, when moved by its appropriate motor 49, will move so that its axis, in any position which it may assume, will remain parallel to the position occupied before such movement. In other words, each of the bars is held or carried by a parallel movement device.

It will be understood that the invention may be embodied in other specific forms without departing from the spirit or essential attributes thereof, and it is therefore desired that the present embodiment be considered in all respects as illustrative and not restrictive, reference being made to the claim rather than to the foregoing description for an indication of the scope of the invention.

What I claim is:

In a printing machine for operating upon a web and having a printing unit for printing register marks longitudinally thereon, a plurality of slitting knives for slitting the web into a plurality of ribbons, turning bars positioned widthwise of the slit web for deflecting and positioning the ribbons so they may be assembled face to face, a parallel movement device for movably holding each turning bar, means for assembling the ribbons face to face, including rollers receiving the ribbons from the turning bars and leading the same to a point of assembly without further turning, a power operated means for adjusting the position of each turning bar, and a control for adjusting the turning bars comprising a scanning head for each ribbon, in position for coacting with the register marks thereof to control the power operated means associated with the turning bar coacting with said ribbon, whereby each ribbon will be positioned in proper transverse register.

ADOLPH M. ZUCKERMAN.
